F.O. Degener
Printing Press

N° 22611.

Patented Jan. 11, 1859.

UNITED STATES PATENT OFFICE.

F. O. DEGENER, OF NEW YORK, N. Y.

PRINTING-PRESS.

Specification of Letters Patent No. 22,611, dated January 11, 1859.

To all whom it may concern:

Be it known that I, FREDERICK O. DEGENER, of the city of New York, in the county and State of New York, have invented a new and Improved Printing-Press; and I do hereby declare that the following is a full, clear, and exact description of the same, reference being had to the annexed drawings, making a part of this specification.

10 In all the figures of the drawings the same letters of reference always denote the same part of the machine.

Figure 1, is a side elevation of my improved "printing press" the side of the frame 15 being removed at the ($x, x,$) line as illustrated by the red line, in Fig. 2, of the drawings. Fig. 2, is a plan of the press, as I arrange it. Fig. 3, shows the relative positions of the bed with its form of types, the platen 20 with its sheet of paper when at the point of contact, or at the time the impression is being taken.

My invention consists in so arranging and combining an oscillating bed with an oscillating platen that while each vibrates upon its own center by means of a third and independent center, is vibrated by a cam so that the movement of such cam shall cause the bed and platen alternately to open and close; when open the sheet is to be placed upon the platen, but when closed the impression is given upon the sheet which had previously been placed upon the platen. This movement is produced by a simple eccentric cam, or crank or some equivalent motion causing both the bed and platen, simultaneously, one with the other, to reciprocate in their motions harmoniously; each being controlled in its relations to the other by the center, or shaft which unites the two at the lower end while each separately revolves upon its own independent center. Also in so arranging the distribution of ink (L), and the inking rollers that the form shall in its transit from one position to the other pass under the inking rollers and thus the form be inked immediately before it arrives at the point of contact; that is, the point of impression. 50 And further my invention consists in so arranging a frisket or grippers which shall receive their motion from the movement of the bed or platen, (either or both of them), in manner to be herein described.

55 To enable those skilled in such like arts,

to make and use my invention I will describe its construction and operation.

In the drawings (A) is the frame of the press, so formed and arranged as to accommodate the various parts of the machine for 60 their different manipulations.

(B) is a shaft, (being the main or driving shaft), having the driving pinion (C) upon it, which gears into (D), upon the shaft (E), at the other end of the shaft (E) 65 is placed a pulley (F).

The toothed wheel (D), is arranged so that the crank or eccentric position will admit of the attachment of the eccentric center to the connecting rod (G) on one side of 70 the press, while (H) occupies a like relation upon the other side of the press. These connecting rods or shackle-bars are connected each to the other by the rods (I).

The form-bed (J) revolves in its reciprocating motions upon its stationary shaft (K), the bed having a flanch upon either side, so that the shaft (K) may pass through and yet remain in its proper position. Upon each side of the bed are the distributing 80 rollers (L).

The platen (M) is jointed to the crank or arms (N) which cranks are loose upon the shaft (O). These shafts (K and O) being located at the two opposite ends of the 85 press.

On either side of the press the platen arms are affixed and will be known as (P, P,); these arms project from the platen at right angles with the shaft (O) the opposite ends 90 thereof being connected with arms on the bed by the movable shaft (Q) which passes through the arms (R, R,) and project from the inner side of the bed (J), that is from the flanches (a).

(S, S) are ink rollers, the journals of which work in the stationary frame.

To the outer end of one of the arms (R, R) a cam (U) is attached. This cam consists of a slot (b) passing entirely 100 through so as to form an open hollow cam; in this a pin projecting from the crank (see C in drawings) is prepared so as to fit in such groove:—this crank (d) is fitted to the end of a shaft (e). To this shaft the ends 105 of two bars ($f, f,$) are attached, and these bars close upon the sheet like a frisket to retain the placed sheet in its proper position upon the platen and there retain it, draw it from the form, and then relieve the same 110

so that the next sheet may be placed in the place itself had occupied.

Operation: Motion being properly given to the shaft (B) the connecting rods will 5 perform their office so that when the bed and platen rotate in their reciprocating motion will advance toward and recede from one another in the proper time. The bed with its form of types passing under the inking 10 rollers so as to ink the form as it passes to and fro. As in the motions, the platen approaches a horizontal position, the bars (f, f₁) are in a vertical position; being governed by the open cam (U) and crank (d). 15 In this arrangement the bars, springs or other contrivance; or frisket if desired or some equivalent thing may be used as a guide to lay the sheet against and there retain it until the proper time for relief. As 20 the bed and platen approach the point of impression, the frisket or its substitute are by the same means brought upon the sheet upon the platen so as to hold the sheet in its place until its proper time for relief. The 25 form of types and sheet of paper to be printed come in contact as they approach the point of impression, as shown at Fig. 3. The printed sheet will at the proper time be removed from the platen; and another 30 sheet will be placed in the position which its predecessor had occupied; when its successor will fill its place and so on continuously.

By this construction the flat surface or bed and platen press is rendered extremely 35 simple and efficient; and the press may be worked rapidly without danger to its working parts.

After thus carefully describing my invention I will remark that my principal dis- 40 covery relates to the bed and platen, so

that the action of one will control the action of the other, and the united movements of either or both of them shall control the action of the frisket or some other instrument which will hold the sheet in its place upon 45 the platen from the time it is placed on the platen, until it has been printed and withdrawn from the form, so that its succeeding sheet shall receive the next impression.

Having thus fully described my invention 50 and its application to use, I will state that I do not claim separately an oscillating bed nor an oscillating platen for these have been previously used. Nor do I claim separately an oscillating frisket, but

55

What I do claim as my invention and desire to secure by Letters Patent, is—

1. So arranging or hanging an oscillating bed with an oscillating platen, in such manner that the motion of one, will control the 60 action of the other—so that by their forward movement they shall close, and give an impression; and upon their reverse movement the form shall be inked, and the platen be brought into the proper position, necessary 65 for the reception of the sheet;—and thus alternate from one of these positions to the other.

2. I claim the arrangement of an oscillating bed and platen as described, with the 70 cam to cause the frisket to assume the desired position so as to hold the sheet of paper while it is being conveyed from one position to the other, all of which is herein described.

F. O. DEGENER.
